UNITED STATES PATENT OFFICE.

STARLEY F. BEASLEY, OF KANSAS CITY, KANSAS.

RAILWAY TANK CAR.

Application filed March 31, 1924. Serial No. 703,321.

To all whom it may concern:

Be it known that I, STARLEY F. BEASLEY, a citizen of the United States, and resident of Kansas City, county of Wyandotte, and 5 State of Kansas, have invented certain new and useful Improvements in Railway Tank Cars, of which the following is a specification and which are illustrated in the accompanying drawings, forming a part thereof. 10 This invention relates to the outlets of railway tank cars, and has for its principal objects to provide a cap that can be easily and quickly applied and removed under all ordinary conditions of service; to provide 15 a cap that can be applied and removed without producing a grinding action on the gasket between the cap and the tube; to provide fastening means for the cap that will permit the outlet to be opened without 20 disconnecting the cap from the outlet tube or leg and that will enable one to quickly and easily close the outlet under pressure of the lading; and to provide a gasket that 25 will endure a long period of service and can be easily resurfaced without special equipment.

Further objects and advantages of the invention will become apparent as the disclosure proceeds and the description is read, 30 in connection with the accompanying drawings illustrating an embodiment of the invention suitable for application to existing cars, and in which —

Fig. 1 is a fragmentary side elevation illustrating the lower portion of the outlet tube or leg, with the cap in closed position;

Fig. 2 is a vertical section of the parts shown in Fig. 1;

Fig. 3 is a transverse section taken on the line 3—3 of Fig. 1;

Fig. 4 is a fragmentary view of the intermediate portion of a tank car; and

Fig. 5 is a fragmentary sectional view 45 of the outlet tube and cap.

Referring to the drawings, 10 indicates the tank which is usually equipped with a dome 11 at the top near the middle. The bottom sheet 12 of the tank is provided with an outlet 13 that communicates with an outlet tube or leg 14 secured to the bottom sheet as shown at 15. In the cars now in general use the tube or leg is externally threaded at 16 to receive a cap 17, which 50 clamps a gasket between finished surfaces 18 and 19 on the tube and cap to make

a liquid-tight joint. The outlet tube is provided with a valve seat 20, and a valve head 21 cooperates therewith to close the outlet.

According to this invention, the cap 17 is replaced by a cap 24 counterbored at 25 to receive the threaded end of the outlet tube 14 with convenient clearance. At the bottom of the counterbore the cap is equipped with a soft metal, preferably lead, 60 gasket 26 for contact with the end of the tube to make a tight seal. The cap may be provided with an undercut groove 22 into which the gasket is fitted. When the gasket is made of metal having a relative low melting point it may be easily formed by introducing the molten metal into the cap and allowing it to cool. The intermediate portion of the cap is provided with an opening 27 of smaller diameter than the tube and a threaded plug 28 closing the opening.

The cap is equipped with lugs 29 in suitable number projecting laterally and perforated to receive clamping bolts 30 for securing the cap in place. The upper ends of the bolts are in this instance supported by an abutment flange 31 screwed on to the threaded end of the outlet tube and locked by the check screw 32.

Preferably the perforations in the lugs 29 take the form of slots 33 that permit the bolts to be swung into position without removing the nuts. The ends of the lugs are provided with depending shoulders 34 that cooperate with the nuts 35 to hold the 80 bolts in place and prevent their swinging laterally in the slots.

The perforations 36 in the flange 31 are preferably enlarged towards the bottom as indicated in Fig. 2, to permit the bolts to 95 be swung to the dotted line position when the cap is to be removed and when a hose or the like is to be threaded on to the tube. The upper surface of the flange 31 is provided with shoulders 37 to cooperate with 100 the heads of the bolts and prevent them from turning when the nuts are being tightened or loosened.

It will be clear from the above that the cap 24 can be much more easily and quickly connected with the tube 14 than the cap 17 can be threaded thereon. The cap 17 is usually set up with a 40" wrench, and the rotation combined with the pressure on the gasket results in an extremely destructive 110 grinding action that renders the life of the gasket 22 very short, and it often happens

that the cap leaks even when a gasket is being used for the first time. The fastening means for the cap 24 involves none of this destructive action, and the gasket may endure throughout a long period of service.

It frequently happens that the valve 21 is not properly seated, and when the cap 17 is removed the liquid begins to flow through the outlet under the entire pressure of the 10 lading in the car. The force of the resulting stream renders it difficult and often impossible to replace the cap. No ordinary foresight can avert this condition, for it is impossible to determine whether the valve is 15 open or whether there has merely been a slight leakage until the cap is entirely removed.

With the improved cap and fastening means the outlet can be opened sufficiently 20 to determine the condition of the valve 38 without losing control of the cap, and should it happen that the valve is open, the cap can be easily and quickly closed with a very small loss of liquid.

25 The nuts on the bolts can be tightened with a very short wrench and yet have sufficient power to properly seal the outlet.

The soft metal gasket not being subjected to anything but direct pressure will last for 30 a long period and when its surface has been marred in use it can be easily resurfaced

by merely setting the cap over a fire, melting the soft metal, and allowing it to cool.

Specific description and illustration have been here used to clearly disclose the invention, but it is not intended thereby to limit the claims or require an interpretation of them that would permit the substance of the invention to be appropriated without liability for infringement.

40 I claim as my invention:

1. In a tank car, the combination of a threaded outlet tube, a flange threaded thereon, a cap for the tube, and bolts connecting the cap and the flange.

45 2. In a tank car, the combination of an outlet tube, a movable abutment projecting laterally from the tube above the low end, a cap closing the end of the tube and having slots in its edge, bolts carried by the abutment and adapted to swing into and out of the slots in the cap, nuts on the bolts and shoulders on the cap cooperating with the nuts to retain the bolts in the slots.

50 3. In a tank car, the combination of an outlet tube, an abutment movably mounted on said tube and having bolt holes therein enlarged at one end, bolts loosely mounted in said holes, a cap for the tube and means carried by the cap for engagement with said bolts.
